UNITED STATES PATENT OFFICE.

ADINE KUNATH, OF NEW YORK, N. Y.

WASTE-PAPER BASKET.

1,237,914.

Specification of Letters Patent. Patented Aug. 21, 1917.

Application filed August 29, 1916. Serial No. 117,441.

To all whom it may concern:

Be it known that I, ADINE KUNATH, a subject of the German Emperor, and a resident of the city of New York, borough of 5 Manhattan, in the county and State of New York, have invented a new and Improved Waste-Paper Basket, of which the following is a full, clear, and exact description.

The invention relates to knockdown receptacles and its object is to provide a new and improved waste paper basket formed of comparatively few parts which can be readily shipped or stored while in flat condition and which can be readily assembled 15 to provide a highly ornamental and exceedingly durable basket for the reception of waste paper and the like.

In order to produce the desired result, use is made of a body consisting of a sheet 20 of flexible material adapted to be bent into tubular form, fastening devices at the ends of the sheet for fastening the said sheet ends together in overlapping relation, supporting and retaining means on the inner 25 face of the said body near the lower end thereof, a slip cover open at both ends and inclosing the said body, the ends of the slip cover telescoping one into the other, and a bottom held within the said body on the said 30 supporting and retaining means.

A practical embodiment of the invention is represented in the accompanying drawings forming a part of this specification, in which similar characters of reference indicate corresponding parts in all the views.

Figure 1 is a perspective view of the waste paper basket;

Fig. 2 is an enlarged sectional plan view of the same on the line 2—2 of Fig. 3;

40 Fig. 3 is a sectional side elevation of a portion of the waste paper basket;

Fig. 4 is a reduced perspective view of the body of the waste paper basket with the supporting and retaining means attached thereto and with the body in flat condition;

45 Fig. 5 is a reduced perspective view of the slip cover; and

Fig. 6 is a reduced plan view of the bottom of the basket.

50 The basket or similar receptacle, in its general construction, consists of a body 10, a slip cover 11 and a bottom 12 held in place within the body 10 by supporting and retaining devices 13 attached to the inner 55 face of the body 10 near the lower end thereof. The body 10 is made of a sheet

of flexible material, such as cardboard, capable of being bent into tubular shape. The ends of the sheet forming the body 10 are provided with fastening devices such 60 as socket members 14 and stud members 15 adapted to engage one the other to fasten the ends together in overlapping relation, as plainly indicated in Fig. 2. The body 10 extends through and is completely hidden in the slip cover 11 made of an outer member 16 and an inner lining 17, the outer member and the lining being fastened together at the upper and lower edges by 65 stitches 18. The outer member 16 is made 70 of a fabric material which is preferably ornamented by embroidery or the like, and the upper and lower edges of this member 16 extends over the top and bottom edges of the sheet forming the body 10, and the 75 lining 17 is made of a suitable fabric lining material and is preferably loose or disposed in light folds, as plainly indicated in the drawings. The lining 17 extends over the supporting and fastening means 13 for 80 holding the cover 11 in place. The bottom 12 is preferably made of a stiff material 85 20, such as cardboard or the like, and completely covered by a fabric material 21.

Each of the supporting and fastening devices 13 is preferably in the form shown in Figs. 3 and 4, that is, each supporting and fastening device consists of a back plate 25 attached by rivets or other fastening means 26 to the inside of the body sheet 10 near the 90 lower end thereof. The attaching plate 25 is provided with a shelf 27 for the bottom 12 to rest on, and from the upper end of the attaching plate 25 extends downwardly and inwardly a spring tongue 28 adapted to engage the top of the bottom 12 to hold the same securely in place and against upward movement. By reference to Fig. 3 it will be noticed that the lining 17 is sufficiently loose 95 to cover the supporting and retaining devices 13 and to allow the bottom 12 to engage the said devices.

From the foregoing it will be seen that the slip covers 11 may be made in various styles and provided with suitable and varying 105 ornaments to suit the taste of a customer. After the customer has selected the desired slip cover, the seller can readily pull the slip cover over a body 10 while the latter is in flat condition and then the body 10 is bent 110 into tubular shape and the ends fastened together by the fastening members 14 and 15.

The ends of the slip cover 11 are now readily drawn over the overlapping ends of the body 10 and telescoped one within the other so that the body 10 is completely inclosed within the slip cover. The bottom 12 is next inserted from the top thereof, and pressed downward so as to temporarily press the spring tongues outwardly until the bottom has passed the free end of the said 5 spring tongues and rests on top of the shelf 27. When the bottom reaches this position the spring tongues 28 return and extend with their free ends above the top of the bottom 12 thus holding the latter securely in position especially against falling out, when the basket is turned upside down for emptying its contents.

The waste paper basket shown and described consists of comparatively few parts 20 which can be shipped or stored while in flat condition and which can be readily assembled to provide a highly ornamental and exceedingly durable basket for the reception of waste paper and the like.

Having thus described my invention, I claim as new and desire to secure by Letters Patent:

1. A receptacle, comprising a body made of a sheet of flexible material adapted to be bent into tubular form, fastening devices at the ends of the sheet for fastening the sheet ends together, a slip cover inclosing the said

body and having an outer ornamental member and an inner lining and a bottom detachably held in said body.

2. A receptacle, comprising a body made of a sheet of flexible material adapted to be bent into tubular form, fastening devices at the ends of the sheet for fastening the said sheet ends together in overlapping relation, 40 supporting and retaining means on the inner face of the said body near the lower end thereof, a slip cover open at both ends and inclosing the said body, the ends of the slip cover telescoping one into the other, and a 45 bottom held on the said supporting and retaining means.

3. A receptacle, comprising a body made of a sheet of flexible material adapted to be bent into tubular form, fastening devices at 50 the ends of the sheet for fastening the said sheet ends together in overlapping relation, supporting and retaining means on the inner face of the said body near the lower end thereof, a slip cover open at both ends and 55 inclosing the said body, the ends of the slip cover telescoping one into the other, the said slip cover having an outer ornamental member and an inner lining, the latter extending loosely over the said retaining means, and a 60 bottom engaging at its edge the said supporting and retaining means and the said lining.

ADINE KUNATH.
